CLAIM

The ornamental design for a linear drive unit, as shown and described.

DESCRIPTION

FIG. 1 is a left, rear perspective view of a linear drive unit according to our novel design;

FIG. 2 is a left side view thereof;

FIG. 3 is a right side view thereof;

FIG. 4 is a top view thereof;

FIG. 5 is a bottom view thereof;

FIG. 6 is a front view thereof;

FIG. 7 is a rear view thereof; and,

FIG. 8 is a right, front perspective view thereof.

The broken lines are for illustrative purposes only and form no part of the claimed design.
